UNITED STATES PATENT OFFICE.

HENRY H. SESSIONS, OF CHICAGO, ILLINOIS, ASSIGNOR TO THE STANDARD COUPLER COMPANY, OF NEW YORK, N. Y.

METALLIC BUFFER-BEAM EQUIPMENT.

SPECIFICATION forming part of Letters Patent No. 643,828, dated February 20, 1900.

Application filed June 19, 1899. Serial No. 721,154. (No model.)

To all whom it may concern:

Be it known that I, HENRY H. SESSIONS, a citizen of the United States, residing at Chicago, in the county of Cook and State of Illinois, have invented a new and useful Improvement 5 in Metallic Buffer-Beam Equipment, of which the following is a specification.

My invention relates particularly to an improvement in the metallic equipment of wooden buffer-beams for passenger-cars; and 10 my object is to simplify greatly the construction of such equipment as well as to strengthen very materially the buffer-beam, the metallic equipment itself, and the connections between 15 said equipment and adjoining parts of the car.

Heretofore it has been the common method to form the head-block or "dead-block," as it is often termed, of wood and to equip said block with a metallic facing, with metallic 20 sleeves or thimbles for the buffer-stems, with a metallic name-plate, (functionally, also, a footboard,) and (in a vestibuled car) with metallic vestibule-post foot-sockets, all of said metallic fittings being separately formed.

25 In my preferred construction all the several metallic parts enumerated, when present, are formed integrally and preferably of malleable iron.

In the accompanying drawings, which illustrate 30 my invention in the preferred form for use in connection with a vestibuled car, Figure 1 is a broken plan view, partly in section, of a buffer-beam and attendant parts equipped with my improvements, the section being 35 taken as indicated at line 1 of Fig. 2; Fig. 2, a view in front elevation of the improved metallic equipment; Fig. 3, a view in rear elevation of the same; Fig. 4, a partly-sectional plan view as indicated at line 4 of Fig. 2; 40 and Figs. 5 to 8, inclusive, enlarged vertical sections at the corresponding lines of Fig. 1.

A represents the buffer-beam; B, its improved metallic equipment; C, the buffer-plate; D, the diaphragm face-plate; E, the 45 side buffer-stems; E', the hinge-plates for pivotally securing the side buffer-stems to the buffer-plate; F, the center buffer-stem; G, the draft-beams of the steel supporting structure of the car, and H a vestibule-post.

50 The equipment B is preferably an integrally-formed malleable casting comprising a

dead-block B', a name-plate B², and vestibule-post foot-sockets B³. The part B² comprises a curved front face-plate a, having a large radius of curvature, lower, center, and upper 55 ribs a¹, a², and a³, respectively, on the rear or concave surface of the plate a, side buffer-stem thimbles or sleeves a⁴, and a center buffer-stem thimble a⁵. The face-plate a is incurved or provided on its front surface with 60 recesses a⁶, to accommodate the side buffer-stem fastenings E'. The center rib a³ is provided with a series of perforated bosses a⁷, at which points horizontal tie-rods a⁸ and other securing-bolts (not shown) pass through the 65 block. Vertical joint-bolts a⁹ and bolts a¹⁰ further secure the block to the buffer-beam and the draft-beams. The upper rib a³ is 70 preferably inclined, as shown, and extends back of the main body of the block, where it is joined by a vertical web b to the inner or back edge of the name-plate B². The plate B² is checkered or roughened over a portion of its upper surface, and, as stated, serves the additional function of a foot-plate. The foot-plate b' of the spring-held buffer-head C moves 75 beneath the plate B² in the usual manner. The space between the upper rib or top a³ of the dead-block proper and the plate B², in fact, affords a recess for the plate b' of the buffer-head to enter when the latter is retracted. The ends of this space are partially closed by 80 reinforcements or fillings b² beneath the foot-sockets B³.

The buffer-beam is properly mortised to receive 85 the thimbles a⁴ and a⁵, the extension of the top rib a³, and the web b, as clearly shown. If desired, the mortises may be made deeper and the center and lower ribs mortised in also.

The above-described manner of forming the 90 improved equipment renders it comparatively light and permits it to be well malleableized. Changes in form and manner of manufacture, however, may be made without departure from my invention. For instance, where the 95 improvement is used with a non-vestibuled car the foot post-sockets are omitted and my invention still used with great advantage. Also, if desired, the equipment may be formed in two parts, the plane of division being indicated by the dotted line 1 of Fig. 8.

It may be remarked that the dead-block

herein claimed is to be distinguished from the light metallic facing of the wooden dead-block above referred to and that the buffer-stem thimbles with which the improved dead-block is provided are to be distinguished from mere perforations in such a facing, it being essential that the stems be provided with metallic sleeves of substantial length.

What I claim as new, and desire to secure 10 by Letters Patent, is—

1. As a new article of manufacture, a malleable cast-metal dead-block for buffer-beams having a curved face-plate and provided on its inner side with projecting buffer-stem 15 thimbles formed integrally therewith and adapted to fit into sockets in the buffer-beam, substantially as and for the purpose set forth.
2. As a new article of manufacture, a metallic dead-block for buffer-beams provided 20 with buffer-stem thimbles and a name and foot plate formed integrally with said block, substantially as and for the purpose set forth.
3. As a new article of manufacture, a metallic dead-block for buffer-beams provided

at its upper portion with a rearward extension formed integrally therewith, and which, in turn, is provided with a forwardly-projecting foot-plate, substantially as and for the purpose set forth. 25

4. A metallic dead-block for buffer-beams, 30 comprising a curved face-plate, ribs integral therewith on the inner side thereof, buffer-stem thimbles on the inner face of said plate and integral therewith, an extension at the upper part, a web carried thereby, and a foot-plate supported by and projecting forwardly 35 from said web, substantially as and for the purpose set forth.

5. A malleable-iron dead-block provided with buffer-stem thimbles and foot-plate 40 formed integrally therewith, said block being recessed to receive the coacting plate of the movable buffer-head, substantially as and for the purpose set forth.

HENRY H. SESSIONS.
